ATTORNEY.

UNITED STATES PATENT OFFICE.

HARVEY E. PARKS, OF CUYAHOGA FALLS, OHIO, ASSIGNOR TO A. M. PARKS,
OF COOK COUNTY, ILLINOIS.

SPLASHER-HOLDER.

SPECIFICATION forming part of Letters Patent No. 433,907, dated August 5, 1890.

Application filed June 8, 1889. Serial No. 313,579. (No model.)

To all whom it may concern:

Be it known that I, HARVEY E. PARKS, a citizen of the United States, residing at Cuyahoga Falls, in the county of Summit and State of Ohio, have invented certain new and useful Improvements in Splasher-Holders; and I do hereby declare that the following is a full, clear, and exact description of the invention, which will enable others skilled in the art to which it appertains to make and use the same.

My invention relates to splasher-holders for wash-stands; and the object of the invention is to provide a holder which is adapted to be attached to the back of a wash-stand at greater or less elevation, and has an adjustable horizontal rod at right angles to the standard for supporting the splasher, and a towel-rack on the standard, and the whole made and finished in artistic form and attractive as an article of furniture, substantially as shown and described, and particularly pointed out in the claims.

In the accompanying drawings, Figure 1 is a front elevation of one of my newly-improved holders as it appears in position on a wash-stand. Fig. 2 is a vertical section of a portion of the standard, showing the means for locking the horizontal rod in position; and Fig. 3 is a cross-section of said standard, likewise showing the cam and the rod, the section of standard in both cases being enlarged. Fig. 4 is a cross-section of the plate of the towel-rack upon the standard, and showing a towel-holder in position for use. Fig. 5 is a cross-section of the standard on line $\alpha\alpha$, Fig. 1, and showing a plan view of the towel-holder plate.

A represents a section of a wash-stand, and B a standard fixed thereto at the back and at one side of the stand by screws b or their equivalent. The standard is shown as raised substantially as far as it will go, but may be lowered at pleasure, thus giving range for taste in this particular and providing for smaller patterns of splasher, when such are preferred. The said standard B may be cast or stamped out of sheet metal, and is provided with a series of openings c on its face, which openings may be of any common or fanciful

form, and are designed to be threaded with 50 ribbon or other material that will give decorative or ornamental effect to the structure. The standard itself is highly finished upon its exposed surfaces, and well suited for the display of feminine skill and taste in the further 55 combinations that are to be made.

In the drawings, the standard is shown as attached at the right of the wash-stand; but if it be more convenient for any reason it can as well be attached at the other side, in which 60 ease the splasher-supporting rod C would project in the opposite direction. This rod is made adjustable in the standard B to adapt it to this change of position from side to side, as well as to adapt it to wash-stands of greater 65 or less width and splashes of greater or less size. The rod C is supported in the right-angled flanges d of the standard B, and locked and held in any desired adjustment by a cam g , which bears against the back of the stand- 7c ard between the flanges. By this construction the means of adjustment are not exposed and are made to answer every purpose. One or both ends of the rod C may be provided with a removable head h , so that said rod 75 can be taken out of its bearings and packed within the flanges of the standard for shipping.

D represents a plate adjustable vertically on the standard B by set-screw K, and provided with openings at intervals to attach the arms M for holding towels. In itself the form of the towel-holder is not new; but it is new so far as I know in the combination here shown and claimed. By releasing the screw 85 k the plate D may be removed from the standard B or adjusted higher or lower, as may be desired.

Having thus described my invention, what I claim as new, and desire to secure by Letters Patent, is—

1. In a splasher-holder, a standard adapted to be attached to the back of a wash-stand and having an opening near its top to support the splasher-rod, in combination with a 95 splasher-rod in said opening free to be adjusted to either side of said standard, and a lock for the rod, whereby the splasher can be

wholly supported on one side or the other of the standard as the case may require, substantially as set forth.

2. In a splasher-holder, a standard having 5 rearwardly-extending side flanges *d*, with opposite holes, in combination with a removable rod supported in said holes and adjustable to either side of the standard, and a lock on the rod between the flanges, substantially as set forth.

3. A standard provided with flanges, as *d*,

in combination with a towel-holder engaging said standard on the edges of the flanges at the rear and provided with a lock bearing against the standard to hold it at different 15 elevations, substantially as set forth.

In testimony whereof I have hereunto set my hand this 29th day of May, 1889.

HARVEY E. PARKS.
